UNITED STATES PATENT OFFICE.

JOSEPH SHACKLETON, OF GREAT FALLS, NEW HAMPSHIRE, ASSIGNOR OF
ONE-HALF TO C. W. WRIGHT, OF SAME PLACE.

DESIGN FOR A STEAM-RADIATOR.

SPECIFICATION forming part of Design No. 12,420, dated August 16, 1881.

Application filed July 21, 1881. Term of patent 14 years.

To all whom it may concern:

Be it known that I, JOSEPH SHACKLETON, a citizen of the United States, residing at Great Falls, in the county of Strafford and State of New Hampshire, have invented a new and original Design for Steam-Radiators, of which the following is a specification, reference being had to the accompanying drawing, forming a part thereof.

10 This design is especially adapted to that class of radiators embodying return-bends concomitant to radiating-pipes; and it consists of cross-ribs upon the return-bends, the radiating-pipes being left plain, and also in the arrangement of the return-bends.

15 The accompanying drawing shows a radiator, in perspective view, containing the design.

The letter A designates the return-bends, and B the radiating-pipes, the latter rising 20 from a base, C, in vertical planes, and the return-bends, being at the upper ends of the pipes, serving to connect them in pairs. The return-bends A are ornamented with cross-ribs, while the pipes B are left plain, and the 25 length of both the return-bends and the pipes gradually increases from the middle to the outside of the apparatus. The return-bends A, moreover, are rectilinear intermediate of their ends.

30 It will be seen that by their arrangement the return-bends A form a triangular figure,

which, by the cross-ribs, is brought in contrast with the remainder of the radiator, thus lending to the article a novel and distinguishing appearance; but the cross-ribs also, in themselves, produce an effect similar to that just named.

What I claim as new, and desire to secure by Letters Patent, is—

1. The design for a steam-radiator, consisting of cross-ribbed return-bends concomitant to plain radiating-pipes, as shown and described.

2. The design for a steam-radiator, consisting of cross-ribbed return-bends of gradually increasing lengths concomitant to plain vertical radiating-pipes of gradually-increasing lengths, as shown and described.

3. The design for a steam-radiator, consisting of cross-ribbed return-bends having gradually-increasing lengths, and having their intermediate portions rectilinear, such return-bends being concomitant to plain vertical radiating-pipes of gradually-increasing lengths, as shown and described.

In testimony whereof I have hereunto set my hand and seal in the presence of two subscribing witnesses.

JOSEPH SHACKLETON. [L. S.]
